UNITED STATES PATENT OFFICE

109,137

DESIGN FOR A GEM SETTING

Joseph Granat, San Francisco, Calif.

Application December 28, 1937, Serial No. 73,915

Term of patent 3½ years

To all whom it may concern:

Be it known that I, Joseph Granat, a citizen of the United States of America, residing at San Francisco, in the county of San Francisco and State of California, have invented a new, original, and ornamental Design for a Gem Setting, of which the following is a specification, reference being had to the accompanying drawing, forming a part thereof.

Fig. 1 is a top plan view of a gem setting, showing my new design;

Fig. 2 is a side elevation thereof; and
Fig. 3 is a bottom plan view thereof.

I claim:—

The ornamental design for a gem setting, substantially as shown.

JOSEPH GRANAT.
